F. J. LIGHTBODY,
HOLDER FOR ROTARY BALLS OR BOBBINS,
APPLICATION FILED APR. 8, 1916.

1,215,824.

Patented Feb. 13, 1917.

INVENTOR:
F. J. Lightbody
by his attorney
ATT'YS.

UNITED STATES PATENT OFFICE.

FRANK J. LIGHTBODY, OF WATERTOWN, MASSACHUSETTS, ASSIGNOR TO CAMBRIDGE NOVELTY COMPANY, OF CAMBRIDGE, MASSACHUSETTS, A CORPORATION OF MASSACHUSETTS.

HOLDER FOR ROTARY BALLS OR BOBBINS.

1,215,824.

Specification of Letters Patent.

Patented Feb. 13, 1917.

Application filed April 8, 1916. Serial No. 89,794.

To all whom it may concern:

Be it known that I, FRANK J. LIGHTBODY, a citizen of the United States, residing at Watertown, in the county of Middlesex and State of Massachusetts, have invented new and useful Improvements in Holders for Rotary Balls or Bobbins, of which the following is a specification.

This invention relates to means for suspending a ball or bobbin of crocheting yarn from the operator's wrist in such manner that the suspended ball is rotatable to give off the yarn as required.

The invention has for its object to provide a simple and effective holder, adapted to be quickly and conveniently engaged with a ball or bobbin, and with the operator's wrist, and to permit free rotation of the ball and prevent downward movement or displacement thereof.

The invention consists in the improvements which I will now proceed to describe and claim.

Of the accompanying drawings forming a part of this specification:

Figure 1 represents a side view of a holder embodying my invention;

Fig. 2 represents a plan view of the ball seat shown by Fig. 1;

Fig. 3 represents a side view of the point guarding support shown by Fig. 1, detached from the bodkin;

Fig. 4 represents a section on line 4—4 of Fig. 3;

Fig. 5 represents a section on line 5—5 of Fig. 1;

Fig. 6 represents a view similar to Fig. 5, showing a modification;

Fig. 7 represents a section on line 7—7 of Fig. 6, and a plan view of parts below said line;

Figs. 8 and 9 represent fragmentary sectional views showing other modifications.

The same reference characters indicate the same or similar parts in all the views.

In the drawings, 12 represents a bracelet preferably of the approximately elliptical form shown by Fig. 1, the material of the bracelet being preferably cylindrical wire.

The elliptical form of the bracelet enables it to be conveniently passed over the operator's hand and brought to a bearing on the upper side of the wrist, the bearing or

line of contact between the bracelet and wrist being limited to the upper side of the 55 wrist by the elliptical form of the bracelet.

13 represents a bodkin suitably connected with the bracelet and projecting therefrom, the bodkin being pointed at its outer end to readily penetrate a crochet ball 14, 60 shown by dotted lines in Fig. 1, and the bodkin being made of cylindrical wire so that the ball is adapted to rotate freely on the non-rotating bodkin.

I prefer to connect the bodkin rigidly with 65 the bracelet and locate the bodkin so that it is substantially in alinement with the major axis of the ellipse formed by the bracelet. The rigid connection of the bodkin with the bracelet enables the latter to 70 be used as a handle whereby the bodkin may be conveniently forced through the ball 14. The bracelet and bodkin may, if desired, be made of a single piece of wire, the portions of the wire which meet to form 75 one end of the elliptical bracelet being united by a solder joint 15.

To prevent downward displacement of the ball on the bodkin and to guard the pointed end of the bodkin which projects through 80 the ball, I provide a point-guarding support which is detachably secured to the bodkin and is adapted to permit rotation and prevent downward movement of the ball.

In the preferred embodiment of my in- 85 vention shown by Figs. 1 to 5 inclusive, the support includes a metal tube 16 having a closed end 17 and longitudinal radial slots 18 subdividing the body of the tube into a plurality of jaws which normally spring in- 90 ward, as shown by Fig. 3. When the outer end portion of the bodkin is forced into the tube the jaws yield outwardly to a slight extent, and maintain a firm frictional hold on the inserted portion of the bodkin. 95

The said support is provided with a seat preferably of greater area than the tube 16, said seat being adapted to bear on the under side of the ball and permit its free rotation. The seat is preferably detachable 100 from the tube and formed by a disk 19 preferably of sheet celluloid having a central hole 21 to receive the bodkin.

The tube 16 and seat 19 may be readily removed from the bodkin to permit the in- 105 sertion of the latter in the ball. After the

insertion of the bodkin in the ball the seat and tube are replaced, the tube engaging the bodkin by friction with sufficient force to support the weight of the ball. The cylindrical form of the wire of which the bodkin is composed permits the ball to be freely rotated by the pull of the yarn of which it is composed.

Figs. 6 and 7 illustrate a modification in 10 which the seat on which the ball rests is attached to the tube 16, said seat being a shell 19^a, which may have radial slots 16^a forming continuations of the tube slots 16.

Fig. 8 shows another modification which 15 includes a tube 16^c which is not slotted and is formed to have a close frictional fit on the bodkin, and a seat 19^c formed by the upper end of a shell attached to the tube. As indicated by dotted lines in Fig. 8, the 20 tapering upper end portion of the shell en-

ters the ball to a slight extent, but not sufficiently to prevent the rotation of the ball.

The support may be a ball 19^d, preferably of wood, having a hole formed to receive and frictionally fit the outer end portion of 25 the bodkin.

Having described my invention, I claim:

A ball holder comprising a bracelet, a ball-piercing bodkin projecting from the bracelet and rigidly attached thereto, the 30 bracelet constituting a handle whereby the bodkin may be forced through a ball, and a point-guarding support detachably secured to the bodkin and adapted to permit rotation and prevent downward movement of 35 the ball.

In testimony whereof I have affixed my signature.

FRANK J. LIGHTBODY.
